Edgar F. & Co.

UNITED STATES PATENT OFFICE.

WILLIAM G. HILL, OF BROOKLYN, NEW YORK.

DESIGN FOR A TOILET-BASIN.

54,089.

Specification for Design.

Patented Nov. 4, 1919.

Application filed April 28, 1919. Serial No. 293,358. Term of patent 14 years.

To all whom it may concern:

Be it known that I, WILLIAM G. HILL, a citizen of the United States, and residing in Brooklyn, in the county of Kings and State of New York, have invented a new, original, and ornamental Design for a Toilet-Basin, of which the following is a specification, reference being had to the accompanying drawing, forming part thereof.

Figure 1 is a plan view of a toilet basin, showing my new design;

Fig. 2 a side view;
Fig. 3 a perspective view; and,
Fig. 4 a front view.

I claim:

The ornamental design for a toilet basin, as shown.

WILLIAM G. HILL.

Witnesses:

C. E. MULREANY,
H. E. THOMPSON.
